Henry Dreyfuss, South Pasadena, Calif., assignor
to The Hoover Company, North Canton, Ohio,
a corporation of Ohio

Application March 18, 1953, Serial No. 24,100

Term of patent 14 years

(Cl. D9—2)

To all whom it may concern:

Be it known that I, Henry Dreyfuss, a citizen of the United States, residing at South Pasadena, in the county of Los Angeles and State of California, have invented a new, original, and ornamental Design for a Suction Cleaner, of which the following is a specification, reference being had to the accompanying drawing, forming a part thereof.

In the drawing:

Figure 1 is a perspective view of a suction cleaner, showing my new design;

Figure 2 is a top plan view thereof;

Figure 3 is a side elevational view thereof;

Figure 4 is an end elevational view of the suction end thereof; and

Figure 5 is an end elevational view of the blower end thereof.

I claim:

The ornamental design for a suction cleaner, substantially as shown.

HENRY DREYFUSS.
